UNITED STATES PATENT OFFICE.

WILLIAM B. DURGIN, OF CONCORD, NEW HAMPSHIRE.

DESIGN FOR A SPOON, &c.

SPECIFICATION forming part of Design No. 20,541, dated March 3, 1891.

Application filed January 21, 1891. Serial No. 378,599. Term of patent 7 years.

To all whom it may concern:

Be it known that I, WILLIAM B. DURGIN, of Concord, in the county of Merrimac and State of New Hampshire, have invented and produced a new and original Design for Spoons, of which the following is a full, clear, and exact specification.

Reference is to be had to the accompanying drawings, forming part of this specification, in which—

Figure 1 represents in plan view a spoon embodying my invention, and Fig. 2 is a side view thereof.

The design consists in the peculiar configuration of the bowl, the lines of the bottom, as seen in side view, forming a compound curve, and the marginal defining lines of the bowl, as seen in plan view, being formed of irregular compound curves at the sides and an outward curve at the front end. The bot-

tom *a* of the bowl, as seen in side view, is of compound-curve shape, the outer terminal *a'* of said compound curve being in a plane above the lowermost point *a²* of said curve.

The marginal defining lines of the bowl, as seen in plan view, consist of the opposed outward curves *b b'* and the opposed inward curves *c c'*, which depart in a forward direction from the outward curves *b b'* and merge into the front outward curve *d*; also, the inward curve *c* is more pronounced than the opposed inward curve *c'*.

I claim—

The design for a spoon, the same consisting in the fanciful configuration of the bowl, as herein shown and described.

WILLIAM B. DURGIN.
